BAILER

Edward F. Westall, Alhambra, Calif.

Application November 22, 1935, Serial No. 51,043

13 Claims. (Cl. 166—19)

This invention relates to vacuum bailers adapted for the removal of drillings, mud, sand or miscellaneous accumulated detritus at the bottom of a well hole or casing.

Bailers of the prior art, such as those adapted for operation by impact against the hole bottom and those incorporating a pump cylinder to draw material into their bucket by raising an outer telescoping cylinder or piston are inefficient and wasteful of both time and energy due to the fact that the force of the impact of the bucket can seldom be great enough, without risk of damage, to embed the mouth of the bucket into the heavier material attempted to be recovered. As a result, subsequent suction created by the upward movement of any part of the bailer is only operative on the more fluent material and frequent repetition of the operation is required to recover the heavier and consequently more objectionable debris.

It is an object of the present invention to fill the bucket hereof by the impact of its precipitation against the material, augmented by the creation of suction in the bucket initiated by the impact, and to thus embed the mouth of the bucket into the material being recovered for further action.

Another object is to create suction in the bucket of a bailer after the mouth of the bucket has been firmly established in the material, and also during withdrawal of the device therefrom to insure a capacity load in one contact.

Other objects and corresponding advantages will be obvious from an examination of the following description and drawing, in which:

Fig. 1 is a sectional view of my invention with the pump cylinder beginning its downward stroke;

Fig. 2 is a section similar to Fig. 1, contrasting the position of valves relative therewith at the beginning of the upward stroke of the cylinder.

Referring to the drawing in detail, the numerals of which indicate similar parts throughout the several views, 5 designates a cylinder which comprises the body of a bucket having an inverted V-shaped lower end or mouth 6. An annular valve insert 7 is secured by rivets 8 or the like within the mouth of the cylinder, to which a mounting 9 for a flap valve 10 is secured. Valve 10 hinged to mounting 9 above the insert 7 permits material to enter the bucket 5 but prevents its egress. A pipe 11, preferably diametrically smaller than cylinder 5, is secured axially above said cylinder by a reducing coupling 12, to which both rod and pipe are threaded. A piston 13, secured to the upper end of pipe 11, by well known

means, is adapted for sliding engagement within a cylinder 14, which is maintained in axial alignment with pipe 11 by a reducing coupling 15 threaded to the lower end of cylinder 14 and slidably encircling said pipe 11.

An internally-threaded annular boss 16 is provided integral with coupling 15 into which a gland 17 is threaded to compress packing 18 and preserve suction within the cylinder 14 below the piston.

At the opposite upper end of cylinder 14 a bail 19 is provided for attachment to a drilling line or the like (not shown). The upper end of cylinder 14 is closed by a standing valve 20 which permits the release of compression caused by the relative upward movement of the piston. A stud 21 welded or otherwise secured to the top of piston 13 provides support for flap valve 22 which is hinged thereto and adapted to close the opening in the pipe 11 upon compression of the fluid within the cylinder above the piston. A port 23 in pipe 11 below the piston is provided with an annular boss 24 which furnishes a flat seat for a flap valve 25. Valve 25 is hinged to a stud 26 mounted, on pipe 11 adjacent the port, by well known means. A port 27 through the wall of the lower end of cylinder 14 is provided with a spring valve 28, riveted or otherwise secured to the wall of the cylinder, through which pressure is relieved on the relative downward stroke of the piston.

As above noted, the device is lowered into the well on a wire or manila line, with the cylinder 14 suspending the piston and bucket. The bucket is then dropped against the bottom of the well hole, causing the loose drillings, sand, and the like, to be forced into the mouth thereof. The downward movement of the piston, being secured with the bucket, is abruptly stopped, and the cylinder continues to drop relative thereto, causing expansion of the chamber below the piston within the cylinder. The suction thus created opens the valve 25 in pipe 11 and closes valve 28 in the cylinder, drawing the material adjacent the mouth of the bucket therein. Fluid pressure above the piston during its relative upward stroke is relieved through the standing valve 20.

Upon completion of its downward stroke, the cylinder is raised by the drilling line, causing reversal of the movement between piston 13 and the cylinder. The expansion of the chamber above the piston will permit the standing valve 20 to close and cause suction to raise valve 22 and close valve 25. Pressure fluid in the cylinder below the piston is then released through valve 28. Thus any relative movement of the piston and cylinder

will cause upward displacement of the fluid within the bucket. Line 35 (Fig. 1) indicates, for example, the level of material in the bailer caused by the impact of mouth 6 with the material, and 5 35' (Fig. 2) the higher level upon completion of the downward stroke of the cylinder. The bailer may then be completely filled on the upward stroke of the cylinder.

By employing a pump cylinder longer than 10 cylinder 5, the fluid displacement therein will be greater than the capacity of the bucket and thus insure filling the bucket with a minimum of strokes.

Conventional means for emptying the bucket 15 upon withdrawal of the device from the well comprises a collar 31, rotatably encircling the lower end of the bucket above valve insert 7 between an annular guide 30, welded or otherwise secured to cylinder 5 above the collar, and member 32 20 which forms the mouth 6 of the cylinder. A hole 33 in collar 31 may thus be brought into registry with a port 34 in cylinder 5 by rotation and the bucket drained of its contents, as is well known.

It will be obvious to those of skill in this art 25 that springs of any well known type may be employed to maintain any or all of the valves in closed position; that various changes may be made in size or type of the valves, relative shape and size of cylinders, as well as in the specific 30 shape of the mouth of the bailer, without departing from the spirit of my invention.

Having described my invention, I claim:

1. In a well bailer, a cylinder, a piston reciprocable within said cylinder, said cylinder being 35 adapted to be raised and lowered relative to said piston, valvular means connected with the ends of said cylinder to release pressure fluid within the cylinder, a conduit from the chambers on opposite sides of said piston within said cylinder 40 to a bailer bucket, and valvular means controlling said conduit adapted to open to suction and close to pressure within the cylinder.

2. In a well bailer, a cylinder, a piston reciprocable within said cylinder, valvular means connected with the ends of said cylinder to release 45 pressure fluid within the cylinder, a conduit from the chambers on opposite sides of said piston within said cylinder to a bailer bucket, and valvular means controlling said conduit adapted to open to suction and close to pressure within the cylinder.

3. In a well bailer, a bucket, a pipe connected 50 with said bucket, a piston connected with said pipe, a cylinder, said piston being slidable within said cylinder, ports to communicate said pipe with the chambers on both sides of the piston in the cylinder, and valvular means controlling said ports adapted to open to suction and close to pressure within the cylinder.

4. In a well bailer, a cylinder and piston adapted 55 for relative reciprocation, having valvular means to relieve pressure within said cylinder on opposite sides of the piston but preserve suction, a bailer bucket, and means to communicate suction, alternately created on opposite sides of the piston, during relative reciprocation of said piston and cylinder, to said bucket.

5. In a well bailer, a bucket, a pipe connected 60 with said bucket, a piston connected with said pipe, a cylinder, said piston being slidable within said cylinder, ports to communicate said pipe

with the chambers on both sides of the piston in the cylinder, valvular means controlling said ports adapted to open to suction and close to pressure within the cylinder, and an inlet valve in the lower end of said bucket to close by pressure from within said bucket. 5

6. In a well bailer, a cylinder and piston adapted for relative reciprocation, having valvular means on opposite sides of the piston in said cylinder to relieve pressure but preserve suction 10 therein, a bailer bucket, and means to communicate suction from said cylinder during each stroke of the piston to said bucket.

7. In a well bailer, a bailer bucket, a vacuum pump slidably connected with said bucket adapted to create a partial vacuum in said bucket by precipitation of the bucket against the matter to be bailed and to further create suction by the elevation of the pump with respect to said bucket. 15

8. In a well bailer, a bailer bucket, a vacuum pump slidably connected with said bucket adapted to create a partial vacuum in said bucket by precipitation of the bucket against matter to be bailed, and to further create suction by the elevation of said pump with respect to said bucket, 20 and means to communicate suction created by said vacuum pump to said bucket. 25

9. In a well bailer, a pump body, a piston reciprocably disposed in said pump body, ports in said pump body at opposite sides of the piston to relieve pressure therein, a bailer bucket connected to said pump body, and means to confine suction created in said pump body on each relative stroke of the piston to said bucket. 30

10. In a well bailer, a vacuum pump comprising a pump body and a reciprocable piston, a bailer bucket, connecting means between the pump and bucket, and means connected to the end of said pump to permit its being raised or lowered, said pump being adapted to create a partial vacuum by both the relative convergence and separation of the bucket and said last-mentioned means, and means to confine the suction created in said pump body by the relative convergence of said bucket and said means for raising and lowering said pump to said bucket. 35 40

11. In a well bailer, a bailer bucket, a pump connected to said bailer bucket comprising a barrel having a plunger therein, means to communicate suction created at opposite sides of the plunger by relative reciprocation of the barrel and plunger with said bucket, and means to close said means to pressure created on either side of said plunger. 50

12. In a well bailer, a bailer bucket having a valve in its lower end adapted to open to a partial vacuum in said bucket and close to pressure therein, and means including a reciprocating pump to create a partial vacuum in said bucket on both strokes of said pump. 55

13. In a well bailer, a bailer bucket having a valve in its lower end adapted to open to a partial vacuum in said bucket and close to pressure therein, and means including a pump connected to said bucket to create a partial vacuum in said bucket by precipitation of the bucket against the matter to be bailed and to further create a partial vacuum in said bucket by elevation of the pump with respect to the bucket. 60 65

EDWARD F. WESTALL.
